UNITED STATES PATENT OFFICE.

ROBERT ROMNEY SPARKS, OF GREENFIELD, MASSACHUSETTS.

INSULATOR-PROTECTOR.

No. 902,262.

Specification of Letters Patent.

Patented Oct. 27, 1908.

Application filed May 20, 1908. Serial No. 433,927.

To all whom it may concern:

Be it known that I, ROBERT ROMNEY SPARKS, a citizen of the United States, residing at Greenfield, in the county of Franklin and State of Massachusetts, have invented a new and useful Insulator-Protector, of which the following is a specification.

This invention relates to insulators for over-head electric conductors and more particularly to a housing or covering for the same.

The object of the invention is to provide a protective jacket or covering capable of being readily placed in position on an insulator and which will effectually house and prevent breakage of the latter and also prevent leakage of the current.

A further object is to provide a jacket or covering having smooth interior walls adapted to frictionally engage the insulator and provided with an external circumferential seating groove for the reception of a line wire.

A still further object of the invention is generally to improve this class of devices so as to increase their utility, durability and efficiency as well as to reduce the cost of manufacture.

Further objects and advantages will appear in the following description, it being understood that various changes in form, proportions and minor details of construction may be resorted to within the scope of the appended claims.

5 In the accompanying drawings forming a part of this specification: Figure 1 is a longitudinal sectional view of a cover or protector constructed in accordance with my invention, showing the same in position on an insulator. Fig. 2 is a perspective view of the cover or protector detached.

Similar numerals of reference indicate corresponding parts in all of the figures of the drawings.

45 The improved cover or jacket forming the subject matter of the present invention is principally designed for use on insulators for telephone or telegraph wires or other over-head electric conductors and, by way of illustration, is shown in position on an insulator of the ordinary construction in which 5 designates the body of the insulator having its interior wall threaded at 6 for en-

gagement with the correspondingly threaded end of the supporting pin 7.

55 The cap or jacket is preferably formed of wood and includes a hollow body portion 8 having smooth interior walls 9 preferably tapered to correspond to the taper of the insulator 5 and adapted to frictionally engage 60 the exterior walls of the latter when placed in position thereon.

The cap or jacket entirely surrounds the insulator so as to effectually house and protect the latter from breakage by stones 65 thrown by malicious persons or by sparks from a locomotive when the insulators are mounted in the vicinity of a rail-road.

Formed in the exterior walls of the cap or jacket 5 is a circumferential groove 10 which 70 takes the place of the groove 11 in the insulator and is adapted to receive the line wire.

By forming the cap or jacket of wood or similar insulating material the jacket not only serves to protect the insulator but also 75 prevents leakage of the current.

In applying the cap or jacket the latter is placed in position over the upper or rounded end of an insulator and said jacket forced downwardly in frictional engagement with 80 the exterior walls of the insulator by tapping the same with a mallet or other suitable tool, thus dispensing with the employment of keys, clamping bands and similar fastening devices for preventing accidental displacement of the cap.

85 It will here be noted that the height of the cap or jacket is slightly greater than that of the insulator proper so that when the cap is positioned on the insulator an intermediate 90 air space or chamber 12 will be formed between the top of the insulator and the adjacent surface of the cap thus allowing the cap to be further adjusted on the insulator should the cap for any reason become loose 95 or wobbly.

100 The exterior walls of the cap or jacket are preferably covered with a coating of tar and creosote in order to protect the jacket from the action of the elements.

While it is preferred to construct the cap or jacket of wood it is obvious that the same may be formed of gutta percha, vegetable fiber or other suitable insulating material, without departing from the spirit of the invention.

From the foregoing description it will be seen that there is provided an extremely simple, inexpensive and efficient device admirably adapted for the attainment of the ends in view.

Having thus described the invention what is claimed is:

1. The combination with an insulator, of a removable jacket forming a housing for the insulator and held in frictional engagement with the exterior walls of the insulator.
2. The combination with an insulator having smooth unobstructed walls, of a removable jacket forming a housing for the insulator and held in position thereon by frictional engagement with the smooth exterior walls of the insulator, the exterior walls of the jacket being coated with a water proof compound.
3. The combination with an insulator having its exterior walls tapered and smooth and unobstructed, of a removable jacket forming a housing for the insulator and having smooth correspondingly tapered interior walls adapted to frictionally engage the exterior walls of said insulator.
4. The combination with an insulator having its exterior walls tapered and smooth and unobstructed, of a jacket forming a housing for the insulator and having its interior walls correspondingly tapered and

smooth and unobstructed and adapted to frictionally engage the exterior walls of the insulator, there being a circumferential wire seating groove formed in the exterior walls 35 of said jacket.

5. The combination with an insulator having its exterior walls tapered and smooth and unobstructed, of a jacket surrounding the insulator and having its upper end 40 spaced from the top of the insulator, the interior walls of the jacket being correspondingly tapered and smooth and unobstructed for frictional engagement with the smooth exterior walls of the insulator, the exterior 45 walls of said insulator being formed with a wire receiving groove.

6. As an article of manufacture, a protective jacket for insulators consisting of a hollow body portion formed of insulating material and having its interior walls tapered and smooth and unobstructed and its outer walls coated with a water proof compound and provided with a circumferential wire receiving groove.

In testimony that I claim the foregoing as my own, I have hereto affixed my signature in the presence of two witnesses.

ROBERT ROMNEY SPARKS.

Witnesses:

HENRY C. SHEPARD,
SAMUEL D. CONANT.
